HERMAN A. DAVENPORT, OF BROCKTON, MASSACHUSETTS, ASSIGNOR TO UNITED SHOE MACHINERY CORPORATION, OF PATERSON, NEW JERSEY, A CORPORATION OF NEW JERSEY.

SOLE-LAYING MACHINE.

Continuation of application Serial No. 265,653, filed December 6, 1918. This application filed May 12, 1921. Serial No. 468,882.

This invention relates to machines for laying soles and is herein illustrated as embodied in a machine for laying upon the bottom of a shoe an unvulcanized rubber sole which is later to be vulcanized.

In laying a rubber sole it is usually desirable, not only to press the sole firmly against the bottom of the shoe, but also to press its margin more or less against the lower portions of the sides of the shoe. In some rubber soled footwear, such as sneakers, the upward bending of the edge or margin of the sole is comparatively slight; but in other types of rubber soled footwear, such as rubber boots and arctics, the margin of the sole is sometimes rolled up around the sides of the boot or shoe for half an inch or more.

In order to provide means for laying various types of soles, one feature of the invention comprises a novel elastic member extending across an opening so that when a lasted shoe with a sole attached is forced against the elastic member and into the opening, pressure will be exerted both directly against the bottom of the shoe and in a direction to bend up the margin of the sole and press it against the sides of the shoe. In the illustrative machine a series of round rubber cords are stretched across an opening in a frame, the ends of the cords being anchored to the frame so that the cords function independently; and, in order to insure a more uniform pressure upon the sole, one or more rubber blankets are laid on top of the series of cords so as to envelop the lower portion of the shoe when the shoe is forced into the opening. Unvulcanized rubber soles are extremely soft and liable to distortion, particularly when a sole is of the type used in producing a rolled edge; and in the laying of such soles the soft rubber blanket lessens or obviates the frictional pull of the resilient member upon the rolled up margin of the sole.

It is particularly desirable that the margins of rolled-edge soles, such as those of arctics, etc., which have been referred to above, be bent up and pressed firmly against the sides of the shoe. To this end, another

feature of the invention comprises means acting through the elastic member to exert such bending up and pressing action. In the illustrative machine there is located beneath the elastic member, which may consist of the cords or blanket, or both, a form or mold the inner edge of the rim of which has an outline corresponding to, but slightly larger than, the outline of the bottom of the shoe. With this construction, when the shoe is forced against the elastic member and into the mold, this inner edge acts through the elastic member both to bend the margin of the sole upwardly and to press it against the sides of the shoe.

One of the results which must be accomplished in properly laying a rubber sole is to express from between the sole and the shoe all air, since otherwise the subsequent heat of the vulcanizing operation will form blisters on the sole. In order, then, to apply additional pressure to the bottom of the sole between which and the shoe air is most liable to be entrapped, another feature of the invention comprises a plurality of pieces of material confined in a container beneath the elastic member. In the illustrative machine the mold is filled partly or wholly with a quantity of small pieces of rubber which may take the form of small rubber balls. When the shoe is forced into the mold in the manner which has been explained above, these rubber balls are both displaced and deformed so that a firm and practically uniform pressure is applied to every point on the bottom of the sole.

These and other features of the invention, including certain details of construction and combinations of parts, will be described as embodied in an illustrative machine and pointed out in the appended claims.

Referring now to the accompanying drawings,—

Fig. 1 is a front elevation of the upper portion of a machine in which the present invention is embodied, a lasted shoe being shown as about to be operated upon;

Fig. 2 is a side elevation of the same parts shown in Fig. 1 but with the lasted shoe omitted;

Fig. 3 is a cross-section on an enlarged scale through the sole laying bed, a lasted shoe with its rubber sole being shown in the position which they occupy before the 5 shoe is forced into the mold;

Fig. 4 is a view similar to Fig. 3 but showing the shoe forced into the mold;

Fig. 5 is a perspective, with certain parts broken away, of the sole laying bed as a 10 whole;

Fig. 6 is a detail elevation showing one form of means for anchoring the elastic cords to the frame;

Fig. 7 is a cross section on an enlarged 15 scale on the vertical portion of line 7-7 of Fig. 3;

Fig. 8 is a cross section through substantially the same structure as that shown in Fig. 7 but taken on the line 8-8 of Fig. 4;

20 Fig. 9 is a cross section of an arctic overshoe and its sole in the same relative position as the shoe and sole shown in Fig. 3, the sole in Fig. 9, however, being considerably wider and being beveled on its upper 25 margin, and

Fig. 10 is a view of the same shoe and sole as are shown in Fig. 9 after the sole has been laid, the edge in this case being a rolled or semi-rolled edge instead of the so-called 30 square edge shown in Fig. 4.

On the drawings a carrier for the sole-laying bed is indicated at 10. In the present instance this carrier moves up and down, its movement being guided by the rods 11, 11, 35 and any suitable mechanism may be employed for moving it up to apply the sole-laying pressure, and for drawing it down after the sole has been laid, the duration of the application of pressure being very short 40 owing to the nature of uncured rubber. A lasted shoe is indicated at 12; and the last 13 is supported against the sole-laying pressure by a heel-post 14 and a toe-post 15. The heel-post 14 is provided with a last pin 16, and the last is provided with a socket 17 for the reception of said pin. The toe-post 45 is provided with a toe-rest in the form of a roll 18 composed of suitable soft material such as rubber. The heel-post and the toe-post 50 are affixed adjustably to an adjustable head 19, the latter being arranged to slide up and down on the guide rods 11, 11. The head is bored and tapped for the reception of adjusting screws 20, 20, the latter being 55 mounted to rotate in a stationary head 21. These screws are sustained against upward movement by shoulders 22 bearing against the under side of head 21, and are sustained against downward movement by the hubs of 60 bevel gears 23, 23. Bevel gears 24, 24 fixed to shaft 25 coat with gears 23, 23 respectively to turn the adjusting screws in unison for the purpose of adjusting the heel-post and toe-post up or down. The shaft 25 is provided

with a hand wheel 26 whereby the adjusting 65 motion may be imparted. The jack posts with their respective heel pin and toe-rest serve as a support for the lasted shoe; and, although in the illustrated machine the lasted shoe is actually carried by this jack-post structure, 70 it will be understood that the term support as used in the claims is intended to apply to any element or structure which will support or back up the lasted shoe against pressure applied to the sole thereof whether such support is movable or stationary. The heel-post and toe-post are adjustable toward and from each other along a ledge formed on the head 19. The shoe-supporting structure, 75 which has been thus briefly described, is or 80 may be substantially the same as that shown and described in Patent No. 1,163,589 granted upon an application filed in my name, and no further description of its details will be 85 given. The mechanism for causing the carrier 10 to be raised and lowered has not been shown since any suitable mechanism may be used which will act rapidly so as not to prolong the pressure upon the uncured rubber sole. Preferably toggle mechanism operated 90 through a one-revolution clutch and controlled by a treadle in the usual manner is provided.

The sole-laying bed comprises a frame 27 and a series of strips or cords 28. These 95 cords are composed of a substance such as what is known in the trade as pure gum rubber, and possess a high degree of elasticity, deformability and flexibility. The frame 27 is formed with an opening, and the cords 28 are arranged to extend in contiguous relation across said opening so as to form a substantially continuous layer or cover, each cord being anchored at both ends to the frame, the anchorage being effected in 100 the present instance by hitch pins 30 projecting laterally from opposite sides of the frame. Although the cords are referred to as separate and distinct elements they may 105 be formed if desired by one or more relatively long strips of rubber or other substance having the qualities hereinbefore ascribed to them. The integral character 110 of the cords in such case is true only in a structural sense, whereas in function the cords are independent of each other. Fig. 5 shows the entire series of cords as comprising three distinct strips or lengths of elastic material, but a single strip of sufficient length would serve the purpose as well, or if desired the cords may be separate one from another and separately fastened to the 115 frame.

In addition to the hitch pins 30 the frame 120 is provided with pins 31 arranged to maintain the cords in contiguous relation to each other. As shown by Fig. 6, the pins 30 and 31 are so spaced that it is necessary to de-

form the cord slightly in order to lace it back and forth across the frame, the cord being thereby anchored securely at both ends of each run with the result that the 5 tension applied to one cord will not be transmitted to an adjacent cord. It follows, therefore, that each cord will sustain the sole-laying pressure applied to it without transmitting the stress to the neighboring 10 cords and without depending upon the neighboring cords to assist it.

To the sides of the frame are hinged covers or guards 33, the longitudinal curvature of the upper edges or faces of which 15 form generally, as will be seen from Fig. 1, to the longitudinal curvature of the bottom of the lasted shoe. The frame 27 is removably held in place on the carrier 10 by dowel pins 35.

20 Located in the opening in the frame 27 is a container or box in the form of a mold 37, the inner edge 137 of the rim of which has an outline corresponding to, but slightly larger than the outline of the bottom of the 25 shoe. The longitudinal contour of the top of the rim, like that of the top of the guards 33, corresponds to the longitudinal curvature of the bottom of the shoe. The mold may be in one piece, if desired, in which 30 case a series of interchangeable molds are used to take care of different sizes of shoes; but in the present case an adjustable mold is shown, said mold comprising two sections 35 slidable toward and from each other on rods or pins, one of which is shown at 39. In order to adjust the parts of the mold, a 40 rod 41 extends through one part and has at each end a hand wheel 45 and a pinion, one of the latter of which is shown at 43. The pinions mesh respectively with racks, one 45 pair of which is shown at 47, 49, one member of each pair being fastened to one part of the mold and the other member to the other part so that rotation of the rod 45 in one direction separates the parts of the 50 mold and in the other direction moves them toward each other. For a purpose presently to be explained, the two parts of the mold are provided at both ends with registering 55 slots 51 in which are located plates 53 so that the ends of the mold are always closed whatever the adjustment of the parts thereof.

With the construction thus far described, 55 the operation of the machine is as follows: A lasted shoe with the sole 100 placed on the bottom thereof is mounted upon the jack-posts in the position shown in Fig. 1 and power is applied to the machine. The 60 effect of this is to cause the whole sole-laying bed to rise and thereby to force the lower portion of the shoe against the series of rubber cords 28. The first part of this motion applies pressure to the bottom of the 65 sole and thereafter the edge or margin of

the sole is bent upwardly and pressed against the lower sides of the shoe, it being understood that the distance from the edge 137 of the mold to the sides of the shoe is somewhat less than the thickness of the 70 cords. In Figs. 3 and 4, the illustrative sole is a comparatively narrow one and is beveled on its lower margin so that at the completion of the operation the sole has substantially a square edge with respect to the 75 bottom. The sole 200, which is illustrated in Figs. 9 and 10, is relatively wider and is beveled on its upper margin so that at the completion of the operation a greater extent of the margin has been bent upwardly and 80 pressed against the side of the shoe. It will be understood, of course, that unvulcanized rubber is very sticky and that as soon as a sole has been pressed firmly into contact with the shoe it will remain in place. It 85 should also be understood that the operation of the machine is a very rapid one, the duration of the application of pressure being about one second.

In order to increase the pressure upon the 90 bottom of the sole, the mold 37 may be partly or wholly filled with a plurality of loose, freely shiftable pieces of material, herein shown as a quantity of small rubber balls 63 which normally fill or practically 95 fill the cavity in the mold, as illustrated in Fig. 3. When the shoe is forced into the mold in the manner illustrated in Fig. 4, these rubber balls are more or less displaced and deformed with the result that a firm 100 and substantially uniform pressure is exerted upon the bottom of the sole. The function of the plates 51, which prevent the escape of the balls from the mold, will now 105 be clear. The bottom of the mold is also maintained closed as will be clear from the construction shown in Figs. 3 and 4.

In order to supplement the action of the 110 elastic cords or, if desired, to take the place of the cords when the rubber balls or similar pieces are used, one or more rubber blankets 65 may be laid upon the cords or upon the rim of the mold. In Figs. 3 and 4, a blanket 65 rests upon the cords 28, the mold being practically filled with rubber balls. In 115 short, all of these elements may be used at the same time; and preferably they are so used, although as has been explained, certain of them may be dispensed with. As has been explained, the uncured rubber of which rubber soles are made or which they contain in large quantity is very sticky. The rubber blanket referred to above is preferably made of pure gum so as to give it the required 120 elasticity and deformability; and it has been found that the soles tend to adhere to the blanket. In order to prevent such adhesion the surface of the blanket may be treated with sulphur chloride or in any suitable 125 manner so as to produce a coat or skin of 130

rubber which is vulcanized to a greater degree than is the body of the blanket. This hardened skin is so thin as not to affect appreciably the flexibility and elasticity of the 5 blanket, and at the same time reduces the tendency to sticking to the sole. Referring now to Figs. 7 and 8, the effect of the rim 137 on the mold will be pointed out more particularly. Fig. 7 is a cross section on the 10 vertical portion of the line 7-7 of Fig. 3 and shows the blanket 65 and the cords 28 in their normal condition. Fig. 8 is a cross section on the line 8-8 of Fig. 4 and shows that the blanket 65 and the cords 28 at this 15 locality have been considerably deformed and are exerting pressure against the side of the shoe. The outline of the inner edge 137 of the mold, as has been explained, corresponds to but is somewhat larger than the 20 outline of the bottom of the shoe, the distance from the edge to the sides of the shoe being somewhat less than the thickness of the elastic member whether said member consists of cords, of blankets or of both. When 25 the shoe is forced into the mold, this edge effects pressure through the elastic member toward the lower portion of the sides of the shoe and thereby bends the margin of the sole upwardly and presses it firmly into 30 place. The purpose of making the illustrative mold in two parts which are adjustable is to permit varying the distance from the inner edge 137 of the mold to the sides of the shoe so as to be able to control the pressure 35 against the sides of the shoe and to provide for shoes of different sizes. The same result can, of course, be obtained either with the illustrative mold or with a one-piece mold by using blankets of different thicknesses or by providing a plurality of blankets and using the desired number with any given shoe.

Although the invention has been described as embodied in a machine for laying unvulcanized rubber soles, it should be understood that the invention is not limited in the scope of its application to the particular machine which has been shown and described.

This application is a continuation so far 50 as common subject-matter is concerned of prior application Serial No. 265,653, filed in my name Dec. 6, 1918, for a sole laying machine.

Having thus described my invention, what 55 I claim as new and desire to secure by Letters Patent of the United States is:

1. A machine of the class described, having in combination, a sole-laying bed, a support for a lasted shoe, and means for producing relative movement of approach between the bed and the support to press the sole of the shoe against the bed, said bed comprising a series of pressure-applying members arranged to function independently of one another to force the sole against the

bottom of the shoe, and means arranged to act through said members to force the margin of the sole against the sides of the shoe.

2. A machine of the class described, having in combination, a sole-laying bed, a support for a lasted shoe, and means for producing relative movement between the bed and support in a direction to press the sole of the shoe against the bed, said bed comprising a series of members arranged to function independently of one another, and means constructed and arranged to operate during said relative movement to exert force upon said members at an angle to the direction of relative movement. 80

3. A machine of the class described, having in combination, a sole-laying bed, a support for a lasted shoe, and means for producing relative movement between the bed and support in a direction to press the sole 85 of the shoe against the bed, said bed comprising a series of members arranged to function independently of one another, and means constructed and arranged to operate during said relative movement to press portions of said members against the sides of the shoe. 90

4. A machine of the class described, having in combination, a sole-laying bed, a support for a lasted shoe, and means for producing relative movement between the bed and support in a direction to press the sole of the shoe against the bed, said bed comprising a series of members arranged to function independently of one another and 100 a mold the inner edge of which has a contour corresponding to but somewhat larger than the contour of the sole of the shoe whereby when the lower margin of the shoe and portions of the members are forced into 105 the mold by said relative movement, said edge will exert, through said members, pressure upon the sides of the shoe.

5. A sole-laying bed comprising a series 110 of pressure-applying members arranged to function independently of each other to press a sole against the bottom of a shoe, and means responsive to pressure of the sole against the members arranged to exert force upon portions of said members in lines 115 transverse to the first named pressure.

6. A sole-laying bed comprising resilient means arranged to press a sole against the bottom of a shoe, and a mold having an internal surface conforming generally to the 120 outline of the bottom of the shoe and arranged to press portions of said resilient means laterally against the sides of the shoe.

7. In a sole laying machine, the combination 125 with means for supporting a lasted shoe, of means for co-operating therewith to apply sole-laying pressure, said means comprising a mold the inner edge of the rim of which has an outline corresponding 130

to that of the sole of the shoe, a series of strips of highly elastic and deformable material bridging across the mold so as to bear on the rim thereof, and means arranged to hold said strips in contiguous relation to one another.

8. A sole-laying bed comprising a mold or form the inner edge of the rim of which has an outline corresponding to the outline 10 of the bottom of a shoe, and a series of strips extending side by side across the mold and supported by the rim so as to exert pressure against the sides of the shoe when pressure is applied through the strips to the bottom of the shoe.

9. A sole-laying bed comprising a mold or form the inner edge of the rim of which has an outline corresponding to the outline of the bottom of a shoe, and a series of 20 strips each rigidly anchored at both of its ends extending side by side across the mold and supported by the rim so as to exert pressure against the sides of the shoe when pressure is applied through the strips to the bottom of the shoe.

10. A sole-laying bed comprising a mold or form the inner edge of the rim of which has an outline corresponding to the outline 30 of the bottom of a shoe, and a series of elastic strips extending side by side across the mold and supported by the rim so as to exert pressure against the sides of the shoe when pressure is applied through the strips to the bottom of the shoe.

35 11. A sole-laying bed comprising a mold or form the inner edge of the rim of which has an outline corresponding to the outline of the bottom of a shoe, and a series of elastic strips each rigidly anchored at both of its ends extending side by side across the mold and supported by the rim so as to exert pressure against the sides of the shoe when pressure is applied through the strips to the bottom of the shoe.

45 12. A sole-laying bed comprising resilient means arranged to press a sole against the bottom of a shoe, and a co-operating backing member arranged to exert pressure through said resilient means against the sides of the shoe entirely around the shoe.

50 13. A sole-laying bed comprising a plurality of rubber cords arranged to press a sole against the bottom of a shoe, and a co-operating backing member arranged to support portions of said cords for pressure against the sides of the shoe.

55 14. A sole-laying bed comprising a mold the inner edge of the rim of which has an outline corresponding to that of the bottom of a shoe, a series of strips bridging across the mold so as to bear on the rim thereof, said strips having a high degree of elasticity and deformability, and anchoring means external of said mold for holding said strips in said relation to the mold.

15. A sole-laying bed comprising a mold the opening in which corresponds in outline to the outline of the sole, a frame, and a series of strips of highly elastic and deformable material stretched across the frame over the opening in the mold. 70

16. A sole-laying bed comprising a mold the opening in which corresponds in outline to the outline of the sole, a frame, and a series of strips of highly elastic and deformable material stretched across the frame over the opening in the mold, each strip being firmly anchored at both ends to the frame. 75

17. A machine of the class described, having in combination, a sole-laying bed, a support for a lasted shoe, and means for causing relative movement of approach between the support and bed, said bed comprising a container, a series of elastic and deformable cords extending across an opening in the container and a quantity of loose, freely shiftable pieces of material in the container beneath the cords. 85

18. A sole-laying bed comprising a mold or form the inner edge of the rim of which has an outline corresponding to the outline of the bottom of a shoe, a series of elastic strips extending side by side across the mold and adapted to be supported by the rim so as to exert pressure against the sides of the shoe when pressure is applied through the strips to the bottom of the shoe, and a quantity of pieces of elastic material in the mold beneath the cords to supplement the pressure on the bottom of the sole. 90

19. A machine of the class described, having in combination, a sole-laying bed, a support for a lasted shoe, and means for causing relative movement of approach between the support and bed, said bed comprising a mold the inner edge of the rim of the open side of which has an outline corresponding to the outline of the bottom of the shoe, a series of elastic and deformable cords extending across the rim, and a backing for the cords comprising a quantity of indiscriminately arranged pieces of material in the mold beneath the cords. 105

20. A machine of the class described, having in combination, a sole-laying bed, a support for a lasted shoe, and means for producing relative movement of approach between the support and bed, said bed comprising a container, a series of elastic and deformable cords extending across the opening, and a plurality of loose pieces of elastic and deformable material in the container beneath the cords. 115

21. A machine of the class described, having in combination, a sole-laying bed, a support for a lasted shoe, and means for causing relative movement of approach between the support and bed, said bed comprising a mold having an open side, a resilient 125

- member extending across the opening and a plurality of loose pieces of resilient material located in the mold beneath the resilient member.
- 5 22. A machine of the class described, having in combination, a sole-laying bed, a support for a lasted shoe, and means for producing relative movement of approach between the support and bed, said bed comprising a mold the inner edge of the rim of the open side of which has an outline corresponding to the outline of the bottom of the shoe, resilient means extending across the rim, and a backing for the resilient means comprising a quantity of indiscriminately arranged pieces of elastic material contained in the mold.
- 10 23. A machine of the class described, having in combination, a sole-laying bed, a support for a lasted shoe, and means for causing relative movement of approach between the support and bed, said bed comprising a container into which the shoe is forced, and a plurality of loose pieces of elastic and deformable material in the container.
- 15 24. A machine of the class described, having in combination, a sole-laying bed, a support for a lasted shoe, and means for causing relative movement of approach between the support and bed, said bed comprising a container into which the shoe is forced, a plurality of loose pieces of elastic and deformable material in the container, and a blanket laid loosely over the rim of the container and located between the sole of the shoe and the pieces of elastic material.
- 20 25. A machine of the class described, having in combination, a sole-laying bed, a support for a lasted shoe, and means for causing relative movement of approach between the support and bed, said bed comprising a container into which the shoe is forced, a plurality of loose pieces of elastic and deformable material in the container, and a comparatively soft flexible blanket of elastic material laid loosely over the rim of the container and located between the sole of the shoe and the pieces of elastic material.
- 25 26. A machine of the class described, having in combination, a sole-laying bed, a support for a lasted shoe, and means for causing relative movement of approach between the support and bed, said bed comprising a mold the inner edge of the rim of which corresponds in outline to the outline of the bottom of the shoe, a layer of elastic material located above the rim, and a plurality of pieces of elastic material in the mold beneath the layer.
- 30 27. A machine of the class described, having in combination, a sole-laying bed, a support for a lasted shoe, and means for causing relative movement of approach between the support and bed, said bed comprising a mold the inner edge of the rim of which corresponds in outline to the outline of the bottom of the shoe, a blanket of elastic material located above the rim, and a plurality of pieces of elastic material in the mold beneath the blanket.
- 35 28. A work-bed for sole-laying, comprising a frame having a cavity, a detachable mold arranged in said cavity, and a series of elastic strips each anchored to said frame and extending across said mold so as to bear on the rim of the latter when in operation.
- 40 29. A work-bed for sole-laying, comprising a frame having a cavity, a sectional mold arranged in said cavity, said mold including a plurality of sections adjustable relatively to each other, and a series of elastic strips each anchored to said frame and extending across said mold so as to bear on the rim of the latter when in operation.
- 45 30. A sectional bed for sole-laying, comprising a mold including sections adjustable toward and from each other, a holder for said mold, and a series of strips anchored to said holder, each of said strips extending across said mold so as to bear upon the rim of the mold, said strips having a high degree of elasticity and deformability.
- 50 31. A sectional bed for sole-laying, comprising a frame having a cavity, a detachable mold having a cavity, said mold being nested with the frame in the cavity of the latter, and a series of strips of highly deformable and stretchable material anchored to said frame and arranged to extend in contiguous relation to each other, across the cavity of said mold to cover the latter said cavity.
- 55 32. A sectional bed for sole-laying, comprising a mold, a series of strips of soft and elastic material stretched across the mouth of the mold, means to maintain said strips in contiguous relation to each other to provide a substantially continuous cover for the mold, and a blanket of soft and elastic material arranged on said strips.
- 60 33. A work-bed for sole-laying, comprising a frame having a cavity, hitch-pins carried by said frame and projecting laterally from opposite sides thereof, a series of strips extending across said cavity and anchored to said hitch-pins, a covering of flexible sheet material arranged upon said strips, and guards connected to said frame, one at each side, each of said guards being formed and arranged to cover the adjacent hitch-pins and confine the adjacent margin of said flexible covering.
- 65 34. In a sole-laying machine, the combination with means for sustaining the lasted shoe, and means for cooperating therewith to apply sole-laying pressure, said means comprising a mold, a series of strips of

- highly elastic and deformable material bridging across the mold so as to bear on the rim thereof, and a covering of highly deformable and flexible sheet material interposed between said strips and the work.
35. In a sole-laying machine, the combination with means for sustaining a lasted shoe, and means for cooperating therewith to apply sole-laying pressure, said means comprising a mold having sections adjustable toward and from each other, a series of strips bridging across the mold and arranged to bear on the rim thereof, a pad of soft flexible sheet material arranged on said strips, and adjusting means arranged to make the rim of the mold finally effective to compress said strips and said pad against the shoe-upper beyond the margin of the sole.
- 20 36. In a sole-laying machine, a sole-laying bed comprising resilient independently mounted strips arranged to press a sole against the bottom of a shoe, and co-operative backing members arranged to press portions of said strips laterally against the sides of the shoe upper, said backing members forming, conjointly a cavity conforming generally to the contour of the bottom of the shoe and being relatively adjustable to vary the degree of lateral pressure imparted thereby.
- 30 37. A sole-laying machine, having in combination, a bed comprising a series of elastic strips for sustaining a sole, a support for a lasted shoe adapted to present the shoe in proper relation to the sole, means for causing relative movement of approach between the support and bed, and means acting through the elastic strips for rolling the edge of the sole up around the lower margin of the upper of the shoe.
- 40 38. In a sole-laying machine, a sole-laying bed comprising a mold the inner edge of the rim of which has an outline corresponding to the outline of the bottom of a shoe, a series of elastic cords extending side by side across the rim, an elastic blanket resting upon the cords, and separate pieces of elastic material located in the mold beneath the cords.
- 50 39. A sole-laying bed comprising a mold, a plurality of pieces of elastic material therein and a blanket extending across the opening in the mold, said blanket comprising a body portion of highly deformable elastic rubber and a skin or surface coat which is harder than is the body portion.
- 45 40. A sole-laying machine, having in combination, a support for a lasted shoe, a resilient member for engaging the sole of the shoe, means for causing relative movement of approach between the support and the resilient member to cause said member to press the body portion of the sole against the bottom of the shoe and to bend the margin of the sole up around the lower side portions of the shoe, and means stationary relative to the resilient member acting through the resilient member for pressing the upwardly bent margin into place.
- 55 41. In a machine of the class described, the combination with a series of elastic deformable cords arranged side by side, means for holding the cords independently under tension whereby when the bottom of a lasted shoe having an unvulcanized rubber sole is pressed against them, the margin of the sole will be rolled up about the sides of the shoe, and means for exerting pressure through portions of the cords to press the margin into firm contact with the sides of the shoe.
- 60 42. A sole laying machine having, in combination, a support for a lasted shoe, a container into which the shoe is forced, a resilient member held across the opening in the container, and a soft rubber blanket located upon the resilient member in position to contact with the bottom and lower side portions of the shoe.
- 65 43. A sole laying machine having, in combination, a support for a lasted shoe, a receptacle having an open side facing the support, a deformable substance filling the receptacle, a member of elastic sheet material held substantially taut across the opening of the receptacle, a blanket of soft easily-deformed material located upon the elastic sheet, and means for causing the lower portion of the shoe to be forced into the receptacle to stretch the elastic member.
- 70 44. A sole laying machine having, in combination, a support for a lasted shoe, a receptacle having an open side facing the support, a deformable substance filling the receptacle, a member of elastic sheet material held substantially taut across the opening of the receptacle, a blanket of soft easily deformed rubber located upon the elastic sheet, and means for causing the lower portion of the shoe to be forced into the receptacle to stretch the elastic member.
- 75 45. A sole laying machine having, in combination, a support for a lasted shoe, a receptacle having an open side facing the support, a deformable substance filling the receptacle, a member of elastic sheet material held substantially taut across the opening of the receptacle, a blanket of soft easily deformed rubber located upon the elastic sheet, and means for causing the lower portion of the shoe to be forced into the receptacle to stretch the elastic member, said blanket being of substantially uniform thickness throughout.
- 80 In testimony whereof I have signed my name to this specification.
- 85 HERMAN A. DAVENPORT.
